UNITED STATES PATENT OFFICE.

WILLIAM McILROY, OF SPRINGFIELD, OHIO, ASSIGNEE OF TWO-FIFTHS TO DANIEL MALONEY, OF SPRINGFIELD, OHIO.

FLOOR, CEILING, AND ROOF CONSTRUCTION.

Application filed December 13, 1923. Serial No. 680,372.

To all whom it may concern:

Be it known that I, WILLIAM McILROY, a citizen of the United States, residing at Springfield, in the county of Clark and State of Ohio, have invented certain new and useful Improvements in Floor, Ceiling, and Roof Construction, of which the following is a specification.

My invention relates to floor, ceiling and roof construction, it particularly relating to a construction of this kind formed of rows of precast blocks with spaces between the rows into which is poured concrete.

One of the objects of my invention is to employ blocks of such a nature as to cause a union between the blocks and the concrete beams or girders to constitute in effect a monolithic structure; a more specific object in this connection being to employ blocks formed of cement and some other substances which will render the blocks highly porous so that when the concrete forming the beams is poured the same will penetrate into the porous blocks and thereby unite the blocks to the beams and cause the blocks and beams to become in effect a single structure.

A further object of the invention is to provide precast blocks in a structure of the character described, which will have the quality of receiving retaining fastening devices, such as nails, so that floor and roofing material as well as certain forms of ceiling may be nailed or otherwise secured directly to the structure if desired.

A further object of the invention is to provide a structure of this character in which the construction will be simplified and cheapened and in which the supporting forms will be of a more simple character, and also in which the construction can be proceeded with under the most severe and unfavorable weather conditions.

A further object of the invention is to provide a structure which will be of the maximum fireproof and sound proof character, an aid to acoustics, a good non-conductor of heat and cold, and of light character compared to other structures of this kind.

A further object of my invention is to provide a structure in which the pouring of a concrete floor may be conveniently discontinued at points in the width or length of the floor.

A further object of the invention is to

provide a structure having a continuous ceiling of porous character to prevent condensation of vapor laden air.

Referring to the drawings:

Fig. 1 is a transverse section of a floor construction embodying the improvements.

Fig. 2 is a similar view showing a modification in the form of the beams.

Fig. 3 is also a similar view showing a further modification in the form of the beams.

Fig. 4 is a vertical section of two of the blocks showing the manner of interlocking the same at the ends.

Fig. 5 is a longitudinal section of a floor construction showing a modification in the form of the beams and also showing the form used during the process of construction.

Fig. 6 is a cross-section of a portion of a floor construction showing a slight modification in the form of the blocks and the method of filling the space between the rows of blocks when more than one row of blocks is employed between the beams.

Fig. 7 is a plan of the construction shown in Fig. 6.

Fig. 8 is a plan view of a floor construction such as shown in Figs. 1, 2 and 5.

Fig. 9 is a cross-section showing a slight modification.

Fig. 10 is a perspective view of the floor construction showing the manner of applying a wooden floor thereto.

Fig. 11 is a cross-section of a floor construction showing a modification in the form of the blocks and also in the form of the beams; this figure also showing one manner of applying a wooden floor and ceiling to the structure.

Fig. 12 is a cross-section of a form of ceiling construction.

Referring to the drawings, 1 represents precast blocks of a highly porous character. The high porosity is secured by a mixture of cement, preferably Portland cement, and a filling material of highly porous character. A satisfactory block possessing such a characteristic may be made of Portland cement and cinders, but good results may be also secured with other substances such as blocks formed of cement and granulated slag, cement and scoria, or cement and pumice. This porous character is due to the cellular structure of the block and in the cases of

slag and cinder block, where the block has substantially $2\frac{1}{4}$ sq. in. of surface it has been found that these blocks are capable of conducting substantially 10 pints of water through and away from the block in 15 minutes and as compared with terra cotta tile and gypsum they have 50 times the conductivity of said last mentioned materials. The blocks are preferably formed hollow 10 for lightness and also when placed end to end of forming conduits 2 to receive electrical cables or conduits, gas or water pipes or other fixtures which may be found desirable to install and conceal from view. 15 In Figs. 1, 2, 3, 5 and 10 inclusive the blocks are shown formed with round openings while in Figs. 6 and 9 they are shown with oval-shaped openings, and in Figs. 11 and 12 with substantially square openings. 20 In erecting the structure a form such as shown in Fig. 5 is employed consisting of suitable supports 3 and 4 upon which are laid strips so spaced as to support the side edges of the precast concrete blocks 1 and 25 to close the lower end of the space between the rows of blocks. The blocks are placed in rows upon the supporting strips 5 and concrete of any usual mixture, such as Portland cement, sand and gravel or crushed 30 stone, is poured into the spaces between the rows of blocks to form beams 6. Each of the blocks has its sides preferably formed with rounded depressions or grooves 7 into which the concrete flows to provide an interlock and the ends of the blocks may also be provided with grooves 8 and tongues 9 so that the blocks interlock in the manner shown in Fig. 4, but the ends of the block 35 may be left perfectly plain if desired. 40 In Fig. 1 the beams are shown as terminating at a point removed from the top of the floor structure so as to provide conduits 10 while in Fig. 2 the lower ends of the beams are shown as terminating at a point 45 removed from the lower surface of the structure to provide conduits 11. These latter conduits may be formed by placing upon the strips 5 a suitable form member (not shown) before the beams are poured. In the other 50 figures the beams or girders are shown as occupying the entire space between the blocks from top to bottom. The conduits 10 and 11 when employed furnish a convenient place for pipes or conduits which are 55 readily accessible for repairs. Before pouring the beams suitable metallic reinforces 12 of any usual character are inserted, an I-beam being shown in Fig. 12 and rods in the other figures. In Figs. 3 and 6 are 60 shown structures in which two or more rows of blocks are placed between the beams with a comparatively narrow space between the rows of blocks which may be filled with concrete as indicated at 13. 65 Roofing material or the flooring, where

wooden flooring is employed, may be applied to the structure in various ways but in all the methods employed the characteristic of the blocks 1 in receiving and retaining nails or other similar fastening devices is utilized. 70 In Figs. 1 and 10 the furring 14 is shown nailed to the blocks 1 and the boards 15 forming the floor nailed to the furring. In Fig. 2 there is shown a cement floor 16 poured upon the floor structure. 75

In Fig. 11 before the beams are poured wooden spacing strips 17 are nailed upon the blocks 1 and after the beams proper are poured the cement is also poured between these spacing strips so as to provide a cement flooring 18. A wooden floor is then placed in position by nailing the furring 19 to the strips 17 and the boards 20 forming the floor proper nailed to the furring. 80

The plastering indicated at 21 forming 85 the ceiling is applied to the lower surface of the structure either directly or by first nailing metal lathing to the blocks, which is the preferable way of doing with the structure such as shown in Fig. 2 where 90 spaces or conduits 11 are left in the lower portion of the structure, the lathing being placed, however, across the channels only. 95

In Fig. 12 is shown a construction in which the ceiling will be constructed entirely of highly porous material. In this view, 1 represents the blocks and 6 the concrete beams. Before setting the blocks and pouring the beams, strips or blocks 22 formed of material similar to the blocks 1 are placed 100 upon the form strips 5 and temporarily secured thereto in any suitable way. These strips 22 act as spacers for the blocks 1 and also act as supports for the reinforcing members 12. The blocks 22 are left in position so as 105 to make a continuous ceiling surface of the highly porous material, the advantages of which are pointed out later. 110

A structure as described presents many advantages over prior structures of the kind. 115

One of the advantages is that the complete structure is in effect monolithic for the reason that in the use of precast blocks of a porous character such as described, the wet concrete forming the beams will penetrate into the material of the blocks and thereby firmly unite with the same. Furthermore it is well known that to avoid the difficulty of having a mix that is too stiff to be workable the maximum strength of the concrete can seldom be obtained in general construction work, whereas with this improved structure there can be used initially an excess amount of water, which within a short time such as 15 minutes, will be conducted away from the beam and it has been demonstrated that this rapid conductivity of the excess amount of water will insure the concrete having the maximum strength 120 or in other words will prevent the beam 125 130

being weakened by the presence of an excess amount of moisture. In this connection it should be explained that it is usual to add more water to the mixture than necessary for maximum strength and that a body of concrete in a form shaped like a frustum of a cone, four inches in diameter at the top, eight inches at the bottom and twelve inches high, which contains substantially ten percent more water than that required for maximum strength, will have a slump of three to four inches when the form is removed. Twenty-five percent more water will give a slump of six to seven inches and fifty percent more water a slump of eight to ten inches.

A further advantage of the use of these porous concrete blocks is that they possess the quality of receiving and retaining nails, screws or other similar fastening devices which permits the application directly thereto of wooden flooring, prepared ceiling such as metal ceiling, and various kinds of shingles, slate and other forms of roofing. Light fixtures, hangers for line shafting and other things of that character may be also readily secured to the blocks.

Other advantages are the ease of construction as the arrangement allows for the use of forms of a more simple character than heretofore employed resulting in a saving of material and also enabling the stops for the concrete beams to be nailed directly to the blocks 1. Another advantage is the ability to work under severe and unfavorable weather conditions because of the fact that the form protects the beams, and the blocks constructed as described, being poor conductors, protect the sides of the beams from frost. Planks placed over the top of the beams furnish the necessary protection at that point. Another advantage is that it is unnecessary to set any blocks of wood for nailing purposes or to set any sleeves for the passage of pipes or conduits.

Another property possessed by these blocks not found in hollow tiling is that the blocks may be readily chipped or cut which enables them to be fitted in irregular places where partial blocks are required and also permits the roofing or floor construction to be opened up to furnish access to conduits or pipes when desired.

Another advantage of the construction is that the rod reinforcements may be secured to the porous blocks by utilizing the nailing qualities of the blocks before pouring the concrete beams which will prevent displacement of the reinforcement when tamping in the concrete of the beams and permits the use of certain kinds of reinforcements which produce stronger beams which are not now extensively used because of difficulty in holding the same in position during the pouring of the beams.

An advantage of the construction shown in Fig. 11 is that the day's work can be conveniently discontinued because of the fact that the strips 17 act as separators for the floor sections 18 which permits the pouring of the concrete to be discontinued after the space between any two of these separators has been filled with concrete.

The construction shown in Fig. 12 is peculiarly advantageous for building structures in which vapor exists in large quantities such for instance as in a paper mill. The blocks 1 as well as the strips or blocks 22 being of a highly porous character, as described, it has been found have the quality of being excellent non-conductors of heat so that the temperature of the under surface of the ceiling does not fall below that of the interior of the room, thus preventing condensation of the vapor on the surface of the ceiling, and the porous character of the blocks also allows diffusion of air through the blocks or passage of vapor laden air therethrough which tends toward evaporation of moisture from the surface of the blocks rather than condensation on the surface of the blocks.

Having thus described my invention, I claim:

1. In a structure of the character described, the combination of precast blocks and a concrete filling formed between said blocks containing an excess amount of water, the blocks being substantially rigid but of such cellular character as to be capable of conducting from the concrete filling and through the block any excess amount of water at a rate such that in the predetermined time required for the concrete to set sufficient excess water will be removed from the concrete to improve the strength and character of the beam. 95

2. In a structure of the character described, the combination of precast blocks and a concrete filling formed between said blocks, the concrete filling being of greater fluidity than the ordinary four inch slump and the blocks being of very openly cellular formation as compared with tile and gypsum, same being capable of conducting water away from the concrete filling at a rate from ten to thirty times as fast as tile or more and in quantity five to ten times as great as tile or gypsum or more whereby the excess amount of water will be conducted away from the concrete during the time that will elapse before the concrete filling can set. 110

3. In a structure of the character described, the combination with two or more rows of precast blocks of very open cellular structure as compared with tile and gypsum and also having the capacity to receive nails and similar fastening devices, concrete filling poured between said blocks, the concrete filling being of greater fluidity than a four 125

inch slump, and the blocks by reason of said open cellular structure being capable of conducting five to ten times or more as much water from the concrete filling as tile and gypsum are capable of doing in the given time within which the concrete filling will set and harden whereby the water flows in

such manner as to cause the filling and blocks to be bonded together in an improved manner.

10

In testimony whereof, I have hereunto set my hand this 8th day of December 1923.

WILLIAM McILROY.
